UNITED STATES PATENT OFFICE

MAE E. LAMBERT, OF DUBOIS, WYOMING

DESIGN FOR A COAT

Application filed May 18, 1929. Serial No. 31,284. Term of patent 3½ years.

To all whom it may concern:

Be it known that I, MAE E. LAMBERT, a citizen of the United States of America, and a resident of Dubois, in the county of Fremont and State of Wyoming, have invented a new, original, and ornamental Design for a Coat, of which the following is a specification, reference being had to the accompanying drawing, forming part thereof.

I claim:

The ornamental design for a coat, as shown,

MAE E. LAMBERT,
